ABSTRACT

The specification discloses a telescopic scaffolding structure comprising upper and lower rigid booms each of which comprises a three-dimensional framework. Between the booms are struts which telescopically engage with one of the booms so that the booms may be moved vertically relative to one another by telescopic engagement of the struts with the one boom and without dismantling the struts. Jacks are provided for gripping the struts and members of the booms to effect the telescopic movement. The structure may be mounted on ground wheels for maneuverability. Various arrangements of boom framework are described and the booms may be interconnected by articulated or telescopic braces which articulate or telescope during relative movement of the booms.

SCAFFOLDING STRUCTURES

CROSS REFERENCE TO RELATED APPLICATION

This application is filed as a continuation-in-part of a copending application Ser. No. 799,001 filed Feb. 13, 1969, now abandoned, and application Ser. No. 51,314 filed June 6, 1972, now abandoned.

BACKGROUND OF THE INVENTION

1. Field of the Invention

The invention relates to a scaffolding structure whose height can be changed and which is useful for shoring and holding shuttering during construction work. From an extended position in which it holds shuttering the structure may be telescoped, moved to a different part of the site and then re-extended to hold shuttering at that part of the site.

2. Description of the Prior Art

Heretofore, telescopic scaffolding structures have usually comprised a rigid framework usually made up of demountable elements and the height of the scaffolding structure has been determined partly by the number of elements included in the structure and partly by jacks between the lower end of the structure and the ground and between the upper end of the structure and the shuttering or the like to be supported. The jacks only give a limited range of adjustment in height and therefore for any large adjustment it has been necessary to add or remove frame elements. Moreover, if it has been desired to move the structure from one part of the site to another it has often been necessary to dismantle it entirely. The object of the present invention is to provide a scaffolding structure whose height may be readily adjusted.

SUMMARY OF THE INVENTION

The invention provides a scaffolding structure comprising: two substantially rigid booms each in the form of a three-dimensional framework and each comprising a plurality of first, mutually parallel members and a plurality of second and bracing members connected between adjacent first members to points adjacent the ends of each first member; a plurality of neutral parallel struts extending between the booms, the struts and the first members of both booms being parallel; the first members of one of the booms being tubular and the struts being telescopically engaged with the tubular first members whereby the booms can be moved relative to one another by telescopic movement of the struts and the first members and means mutually to locate each strut and the first member with which it is telescopically engaged.

BRIEF DESCRIPTION OF THE DRAWINGS

The invention will now be described in detail by way of example with reference to the accompanying diagrammatic drawing in which:

FIG. 1 is a side elevation of one form of scaffolding structure in accordance with this invention;

FIGS. 2 and 3 are end elevation and plan view respectively of the structure depicted in FIG. 1;

FIG. 4 is a perspective view of one of the end members of one of the struts of the construction depicted in FIGS. 1 to 3;

FIG. 5 is a side elevation similar to FIG. 1 but showing a modification;

FIG. 6 is the side elevation similar to FIG. 1 but showing a further modification;

5 FIGS. 7 to 10 inclusive are detail views of four optional accessories for use with the structures in accordance with the invention;

FIG. 11 is a side elevation of another form of scaffolding structure in accordance with the invention;

10 FIG. 12 is a section through part of the scaffolding structure of FIG. 11;

FIG. 13 is a detailed view of the first member having integral flanges and showing the connection of the second members;

15 FIG. 14 is a plan view of FIG. 13;

FIG. 15 is a section through another type of first member having a flange welded thereon;

FIG. 16 is a plan view of the first member of FIG. 15;

20 FIGS. 17 and 18 are partial sections through further forms of the first member;

FIGS. 19 and 20 are partial side elevation and plan respectively of the first member having a collar thereon;

25 FIGS. 21 and 22 are side elevations and plan respectively of part of a boom showing crossed second members;

FIGS. 23 and 24 are plan views of two forms of boom having crossed and parallel second members;

30 FIGS. 25 and 26 are an elevation and a plan of parts of a boom having crossed second members;

FIG. 27 is an elevation of a structure embodying the invention showing diagrammatically braces between the booms;

35 FIG. 28 is a detailed view of the structure of FIG. 27 showing an articulated brace;

FIG. 29 is a plan view of the arrangement shown in FIG. 28; and

40 FIG. 30 is a detail of the structure shown in FIG. 27 but showing a telescopic brace.

DESCRIPTION OF THE PREFERRED EMBODIMENTS

45 Referring firstly to FIGS. 1 to 4 of the drawings, the scaffolding structure there illustrated comprises a pair of horizontally extending substantially mutually parallel rigid booms 10 connected together near their ends in vertically spaced relationship by vertically disposed telescopically adjustable struts 11.

50 Each boom 10 comprises a plurality of parallel first members and each strut 11 comprises an intermediate assembly 13 in the form of a tube of smaller diameter than that of the tubes forming the first members 12 so as to be telescopically slidably within each end thereof.

55 Each intermediate assembly 13 is formed at equal intervals along the length thereof with pairs of holes 14 adapted to receive detachably one of two load pins 15 provided for each intermediate assembly 13, opposite ends of each pin 15 abutting against end flanges 16 which are provided on the opposed ends of the first members 12 of the two booms as well as on the other ends of these members.

60 65 Each first member 12 is provided at each end thereof on the inner face of each flange 16, with four flat lugs 17 the planes of which are both radial and parallel to

the central longitudinal axis of each member 12, with the lugs 17 spaced equidistantly around such axis.

The lugs 17 are apertured to receive pins 18 connecting the lugs to the ends of second and bracing members 19, 20 extending diagonally in directions respectively across the width of and along the associated boom 10 and to the next parallel and adjacent member 12.

Thus the first members 12 and the second and bracing members 19, 20 constitute each of the two booms 10. These may further embody additional horizontal bracing elements 21 which connect together intermediate their ends pairs of diagonally extending mutually crossing members 19, 20. Where the two members 19 and 20 cross one another they are connected together by pins 22 so as with the elements 21 to further increase the rigidity of the booms.

In so far as the intermediate assembly 13 of each strut 11 telescopes within each first member 12, the latter can as shown be formed as a cylindrical tube the wall of which is continuous around the tube and at the same time both ends of each member 12, i.e. including the end nearer to the assembly 13 can be connected through the lugs 17 to the bracing members 19, 20 without interfering with the telescoping of the struts in the first members 11.

Also in so far as both ends of each first member 12 are secured to the bracing members 19, 20 of each boom, the first members 12 are held very rigidly against relative lateral movement, i.e., are maintained in alignment with one another, thus ensuring to the maximum extent that the structure will not fail by bending but only by buckling, i.e., will fail only if loaded substantially in excess of the safe bending load of the first members 12 and struts 11.

Adjustment in the overall height of the structure is effected by suitably selecting the position of one or both load pins 15 in relation to the pairs of holes in the corresponding end portions of each intermediate assembly 13 so as to vary the distance by which the intermediate member telescopes within one or both first members 12, as well as to bring the two booms into close proximity with one another to facilitate storage or transport of the structure.

As shown, each intermediate assembly 13 is formed in two aligned sections 13a, 13b connected rigidly but detachably together through integral abutting flanges 23 secured to one another by removable bolts 24 which bolts may be also connected to the ends of intermediate bracing bars 25 which extend horizontally between adjacent mutually parallel struts 11 so as to reduce the liability of the struts failing by bending.

The construction of each intermediate assembly 13 in two sections connected together by bolts permits if desired of the two sections being separated and used as two separate intermediate members 13a, 13b each telescoping within a corresponding first member 12 as shown in FIG. 5; the two intermediate members 13a, 13b each receiving telescopically therewith one of two intermediate members forming sections 13c, 13d respectively and connected together by flanges 23 as in the case of the sections 13a, 13b in the FIG. 1 construction, to form an intermediate assembly similar to the member 13 of FIG. 1 but of smaller diameter. Each section 13c and 13d is provided with pairs of adjusting holes 14 receiving a corresponding load pin 15 the ends of which abut against the flange 23 on the sections 13a 13b. With such an arrangement although the maximum

spacing of the two booms 10 may be approximately twice that of the construction of FIGS. 1 to 4, insofar as each intermediate member section 13c, 13d can telescope substantially completely within the sections 13a, 13b respectively and the latter can telescope within the adjacent end member 12, the structure can still be collapsed to a minimum height which is only slightly greater than that of the construction of FIGS. 1 to 4.

The arrangement of FIG. 5 can be further developed 10 to provide as shown in FIG. 6 for a third boom 10a intermediate the two booms 10 already mentioned and extending parallel thereto, while still providing the important feature that when fully collapsed the overall height of the structure is substantially the sum of the 15 overall depth of the several booms.

This is achieved by re-arranging the four intermediate member sections 13a, 13b, 13c of FIG. 5 in the manner depicted in FIG. 6, as is permitted by the detachable connection between the sections. Thus the

20 two larger diameter sections 13a, 13b are now respectively telescopically slidable within a first member 12 of one of the two booms 10 and the intermediate boom 10a, with these sections 13c, 13d respectively being telescopically slidable within the sections 13a and 13b.

25 The flanges 23 of the sections 13a and 13b are connected to the end flanges 16 on the end members 12 of the other boom 10 and intermediate boom 10a. For this purpose the holes 16a of the flanges 16 are disposed in alignment with the bolt receiving holes in the flanges 23 to which the flanges are connected by the bolts 24. The versatility of this arrangement is self evident.

By providing the intermediate boom 10a the resistance to buckling of the struts of an otherwise similar structure of the same overall height is substantially 35 doubled.

Referring now to FIGS. 7 to 9 of the drawings, there are here depicted various arrangements for effecting adjustment in the overall height of the scaffolding structure.

40 In one arrangement depicted in FIG. 7 an electrically driven screwjack is provided comprising a motor and reduction gear unit 26, which drives a screw 27 carrying a nut 28 articulated to a first self-clamping fixing device 29, applied to a first member 12. The motor and reduction gear unit 26 is fixed to a frame 30 which protects the screw 27 and is articulated to a second self-clamping device 31 which transmits the force to one of the intermediate assemblies 13. In order to prevent any flexing of the screw 27, the latter is suspended from the shaft of the motor and reduction gear unit 26, its bottom end being free or guided in a simple manner; thus, it operates purely in tension whilst the frame 30, operates in compression.

45 Each of these self clamping devices comprises levers 32, 33 respectively and which are respectively hinged at their one ends through pivots 34 to the nut 28 and frame 30. Each lever 32, 33 carries at two positions spaced along the length thereof a pair of jaws 35, 36 which respectively engage frictionally but detachably with opposite sides of the members 12, 13. The jaws 35, 36 are articulated through pins 37 to their respective levers. As the jack is operated to extend the associated strut against the weight of the upper boom, the levers 32, 33 as a result of the frictional engagement between the jaws 35, 36 and their respective members, tend to

50 rock about their respective pivots 34, without the jaws advancing along the members 12, 13 so that the jaws 55 55 60 65 60 65

are caused to bind on the members 12, 13 with a force which increases with the load resisting the extension movement of the strut. Thus the greater the load applied by the upper boom to the strut the greater the resistance to slip between the jaws and the members 12, 13 so that provided sufficient power is supplied by the motor unit 26 the required adjustment in the height of the structure will be effected.

The arrangement of member engaging jaws depicted in FIG. 7 possesses the further advantages that:

- a. It permits items to be attached at any desired point on a smooth tube, with any desired angular orientation.
- b. The fixing is positive, that is to say no sliding under load is possible since the clamping load exerted by the jaws rises more steeply than the sliding force introduced by the load.

Other forms of jack, e.g., hydraulic may be similarly connected to the two relatively extensible members of each strut.

As will be readily apparent from FIGS. 1 to 6 the effect of applying extending force from a jack as above described is necessary to remove the load on the load pins 15 and permit of their removal. When however it is desired to remove a pin without extending the structure by a power operated jack this is much more difficult because of the load engagement between the pin ends and the part abutting thereon, e.g., flange 16 in FIG. 3.

The foregoing is taken care of with the arrangement depicted in FIG. 8 comprising providing between the load pin 15 and flange 16 or if desired flange 23, a ring 38 rotatably mounted on the strut member having the pin receiving holes 14, i.e., assembly 13 as illustrated, the ring 38 carrying a pair of diametrically opposed cams 39, of which only one is illustrated, with the crests of which cams opposite ends of pin 15 engage when under load. Rotation of the ring relative to flange 16 or 23 is normally prevented by securing peg 40 to retain the parts in the position shown in FIG. 8.

In operation, the upper boom may be supported by one or more ordinary-screw jacks extending between it and the lower boom. The peg 40 is now removed, the ring 38 rotated by striking its arm 41 with a hammer to bring the cams 39 clear of the ends of pin 15 which can now be withdrawn since the load is taken wholly by the screw jack or jacks mentioned.

If, instead of mechanical or electric jacks, hydraulic jacks supplied from an electrically driven geared pump (or any other kind of pump whose direction of rotation is fixed), are used, then it is advisable where the motor driving the pump is of the three-phase or two-phase type, to provide a device which makes the motor rotate in the correct direction, however it is connected to the mains. FIG. 9 illustrates a particularly simple device for this purpose.

On the spindle 42 of the electric motor 26, or upon a shaft driven directly or indirectly thereby, there is carried an arm 43, suitably lubricated to prevent any binding. A tension spring 44, one end of which is fixed to the arm and the other to a fixed point, load the arm 43 into contact with the drive shaft so that the arm 43, driven by the friction forces or the viscosity of the lubricant, tends to rotate in the same direction as said shaft 42. However, two stops 45 and 46 limit its rotation. If the motor starts to rotate in the proper direction, indicated by the arrow 47, then the arm comes

into contact with the stop 45, and nothing further happens. If, however, the motor 26 starts to rotate in the wrong direction, then the arm 43 is driven towards the stop 46 but before reaching it, engages the operating member 48 of the changeover switch 49, which is displaced to reverse the polarity of the current supply circuit 50 of the motor 26 so as to reverse the direction of rotation of the motor and thus ensures proper operation. Although in the embodiment illustrated hereinbefore, the arm 43 is driven by friction or by the viscosity of the lubricant, other drive media may be employed, hydraulic, aerodynamic, magnetic and so on. In the latter instances, the arm 43 is not necessarily carried on the shaft whose direction of rotation is being monitored, but may be articulated to a shaft rotating in the direction of rotation of the motor, or may for that matter be replaced by another kind of moving device whose direction of displacement is determined by the direction of rotation of the motor. The changeover switch can equally well be controlled in different ways, for example, in a direct mechanical manner, by electro-mechanical relays, by hydraulic or magnetic action, through the medium of a photo-electric cell, through a capacitive cell and so forth.

The form of member engaging jaws depicted in FIG. 7 may be applied to the attachment of a transporting wheel to the structure to facilitate its maneuvering, e.g. on site. For this purpose the two jaws 35, 36 already described are similarly articulated to an arm 51 instead of to the levers 32, 33 of FIG. 7. The arm 51 at its free end carries a ground engaging wheel 52. Under the effect of the load carried by the wheel 52, the jaws 35 and 36 clamp around the first member 12, the clamping force being the higher the greater the load, as already described in connection with FIG. 7.

Referring now to FIGS. 11 and 12, this shows a scaffolding structure indicated generally at 53 comprising an upper boom 54, an intermediate boom 55 and a lower boom 56. The upper boom comprises first members 57 which are parallel and which are interconnected by second members 58 which brace the first members and are connected between adjacent first members to points adjacent each end of each first member as will hereinafter be described. The boom is a three dimensional structure, there being further first members 57 behind those shown in FIG. 11 and which are connected to those shown in FIG. 11 by further second members 58. The boom can be of any designed size and forms a three dimensional framework. The second members 58 are in turn braced by members 59. The intermediate boom comprises first members 60 similar to the members 57 and interconnected in the same way by second members 61. In this boom there are further bracing members 62. The lower boom 56 is identical to the intermediate boom 55 and comprises first members 63, second members 64 and bracing members 65. There are struts 66 between the upper and intermediate booms and struts 67 between the intermediate and lower booms. Each strut 66 comprises an outer tube 68 and an inner tube 69. As shown in FIG. 12, each outer tube 68 is slidable in the first member 60 and is guided therein. Each inner tube 69 is slidable in its associated outer tube 68 in a similar manner. Each inner tube 68 has a series of spaced apertures 70 and each inner tube has a series of spaced apertures 71. Each outer tube 68 is provided at its upper end with a flange 72 and each

inner tube is provided at its upper end with a flange 73.

Each first member 60 is tubular and is provided at its end with flanges 74 and 75. In a similar manner each first member 57 is provided at its ends with flanges 76 and 77. The flanges 77 and 73 of each first member 57 and immediately adjacent inner tube 69 are secured together by bolts, not shown.

The boom 54 can be moved vertically relative to the boom 55 by telescoping movement of the inner tubes 69 in the outer tubes 68 and of the outer tubes 68 in the first members 60. Locking pins, not shown, are provided to enter the apertures 70, and 71 and engage the flanges 74 and 72 respectively whereby the spacing between the booms 54 and 55 may be altered.

A similar arrangement is provided between the booms 55 and 56. Thus the struts 67 have outer tubes 78 with flanges 79 and inner tubes 80 with flanges 81. The first members 63 have flanges 82 and 83. The adjacent pairs of fingers 75 and 81 are interconnected by bolts, not shown, and the spacing between the booms 55 and 56 can be adjusted by telescoping movement of the inner tubes 80 into the outer tubes 78 and of the outer tubes 78 into the first members 63.

The flanges at the ends of the first members may be provided in a number of ways. Thus referring to FIG. 13, this shows a first member 84 which is secured to second members 85 and the flanges at the ends of the first member 84 are indicated at 86 and are formed integrally with the member by forging or other suitable means. It will be seen from FIG. 14 that the second members 85 are parallel and are bolted at their ends to spaced holes 87 in the flange 86. It will also be noted from FIGS. 11 to 13 that the second members of the various booms extend diagonally between the first members of each adjacent pair of first members when viewed in directions perpendicular to the length of the first members.

FIGS. 15 and 16 show an alternative means of providing flanges at the ends of the first members. In this arrangement a first member such as 87 comprises a tube 88 which has its end portions received in pre-formed flanges 89 which are welded in position. Each flange 89 has a number of holes 90 equiangularly spaced about its centre.

FIG. 17 shows a still further method of providing a flange 91 on a tube 92 forming part of a first member, the flange 91 being welded to a sleeve 93 which in turn surrounds and is welded to the end portion of the tube 92.

FIG. 18 shows a still further method of securing a flange 94 to a tube 95 forming part of a first member. The flange 94 is annular and receives the end portion of the tube 95, the end portion being welded at 96 to the flange.

All the arrangements shown in FIGS. 13 to 18 provide anchorages for the ends of the second members such as 85 which cannot become detached from the first member due to a load transverse to the longitudinal axis of the first member. Thus in FIGS. 13 and 14 the flange is integral and in the remaining figures the flange surrounds and is engaged by the end portion of the member so that it cannot come away therefrom. Even if the end location of the flange fails in the arrangements of FIGS. 15 to 18, this may allow the flange to slide along its associated tube but this will not cause any serious dislocation of the structure.

Referring now to FIGS. 19 and 20, this shows how a collar indicated generally at 97 is secured about the end portion of a tube 98 forming part of the first member. The collar 97 comprises four generally U-shaped parts 99, 100, 101 and 102 the adjacent limbs of adjacent U-shaped parts being welded together at 103 and also being connected by bolts 104. The collar is located endwise by a ring 105 which is welded to the tube 98. As will be seen from FIGS. 19 and 20 a second member such as 106 may be secured to the collar by one of the bolts 104. The collar is prevented from becoming disengaged from the tubes 98 by means of the bolts 104, the welds 103 taking little part in the transverse transmission of force from the second member 106 to the tube 38.

Referring now to FIGS. 21 and 22, these show part of a boom indicated generally at 107 and comprising four first members 108, 109, 110 and 111 provided with flanges at their ends as described above. The first members 109 and 111 are interconnected by second members 112 and 113 which as shown in FIG. 22 cross when viewed in directions parallel to the longitudinal axes of the first members. The second members 112 and 113 also extend diagonally between the first members 109 and 111 when viewed in directions perpendicular to the lengths of the first members and where the second members 112 and 113 cross they are interconnected as indicated at 114. It will be seen from the dispositions of the connections of the ends of the second members 112 and 113 to the flanges at the ends of the first members 109 and 111 that the latter are prevented from rotating about their own axes. In a similar manner, the first members 108, 109 are connected by crossed and interconnected second members 115 and first members 108 and 110 are interconnected by crossed and interconnected second members 116 and the first members 110 and 111 are connected by crossed and interconnected second members 117. It will be appreciated that two booms such as shown in FIG. 21 and 22 will be interconnected by struts in the manner described in relation to FIGS. 11 and 12.

Referring now to FIG. 23, this is a plan view of a boom comprising three first members 118, 119 and 120 arranged at the apices of a triangle. The first members 118 and 119 are interconnected by second members 121 which are arranged in parallel planes but which extend diagonally as shown in FIG. 21 between the first members when viewed in directions perpendicular to the length of the first members. In a similar manner the first members 118 and 120 are interconnected by second members 122. The first members 119 and 120, however, are connected by crossed second members 123 arranged as described in relation to FIGS. 21 and 22, the second members being interconnected thus preventing rotation of the first members 119 and 120 about their longitudinal axes. The dispositions of the second members 121 and 122 also prevent the first member 118 rotating about its longitudinal axis.

FIG. 24 shows a plan view of a boom with the first members at the corners of a parallelogram. The first members are indicated at 124, 125, 126 and 127. The first members 124 and 125 are interconnected by second members 128 which lie in parallel planes but are diagonal as described above and in a similar manner the first members 126 and 127 are connected by second members 129. The first members 124 and 126 are interconnected by crossed and interconnected second

members 130 and the first members 124 and 125 are connected by crossed and interconnected second members 131, the members being crossed and interconnected as described in relation to FIGS. 21 and 22. It will be seen that the first members are prevented from rotating about their own axes by the disposition of the various second members.

It will be appreciated that the booms of FIGS. 23 and 24 respectively will be interconnected with similar booms by struts in the manner described with reference to FIGS. 11 and 12.

Referring now to FIGS. 25 and 26 these show a further boom embodying the invention. There are four first members 132, 133, 134 and 135, the members 132, 133 and 134 being arranged at the apices of a triangle and the first member 135 being arranged at the mid point of the base of the triangle. The boom consists of two sets of first members interconnected, the second set corresponding to the members 132 to 135 and being indicated at 132a to 135a respectively. The flange at the lower end of each upper first member is bolted to the flange at the upper end of the corresponding lower first member. For example the flanges on the members 132 and 132a and indicated at 136 and 137 respectively and are bolted together.

The first members of each set are interconnected by second members. The first members 132 and 135 are connected by crossed and interconnected second members 138, the first members 133 and 135 are connected by crossed and interconnected second members 139 and the first members 134 and 135 are connected by crossed and interconnected second members 140 all arranged as described in relation to FIGS. 21 and 22. The first members 132 and 134 on the one hand and 133 and 134 on the other are interconnected by second members 141 which are arranged diagonally. The various first members are prevented from rotating about their longitudinal axes in the manner described above.

Referring now to FIG. 27 this shows a scaffolding structure embodying the invention with a first boom 142 and a second boom 143 and with struts 144 between the booms. In this construction the struts 144 telescope within the first members 145 and 146 of the boom 142. The first members of the boom 142 are braced to the first members 147 and 148 of the boom 143 by braces 149. The braces 149 are either articulated or telescopic.

Referring to FIGS. 28 and 29 these show telescopic braces between the first members 145 and 148. The brace is indicated generally at 150 and comprises two parts 151 and 152. The parts are articulated at 153 and extra holes are provided in the parts at 154 to allow the axis of articulation to be moved. The part 151 has a series of holes 155 in its end portion spaced lengthwise along the part and the part 152 has a series of holes 156 similarly arranged. To the lower flange 157 of the first member 145 there is secured a square fixing element 158 having a series of holes 159 in each side spaced apart in a direction perpendicular to the longitudinal axis of the member 145. In a similar manner, the flange 160 at the upper end of the first member 148 is provided with a square fixing element 161 which has in each side a series of holes 162 which are spaced apart in a direction transverse of the longitudinal axis of the first member.

When the structure is in use, the parts 151 and 152 are locked in position by a pin 163 which passes through aligned holes in the parts. The ends of the braces are secured to the fixing elements 158 and 161 by engaging bolts in the holes in the fixing elements and in the end portions of the braces. Due to the spacing and arrangement of the holes in these parts the braces can be readily adjusted for different spacings of the booms. If it is desired to lower the first boom as indicated in dotted lines for the first member 145, the pin 163 is removed and the brace may be articulated as shown in dotted lines without being removed from the booms. Thus, if the structure is to be telescoped to be moved to a different position then this can be done by articulating the booms without having to remove them.

FIG. 29 shows how there may be two braces, one on each side of the first members, the second brace being indicated at 164 and being similar to the brace 150. In this way, the braces remain clear of the second members during relative movement of the booms.

Referring now to FIG. 30, this shows an arrangement similar to FIG. 28 except that the brace between the two booms which is indicated at 165 is telescopic and comprises an outer part 166 and an inner part 167. The inner part 167 has a series of holes 168 which may be brought into alignment with any one of a series of holes 169 in the outer part 166 so that the parts may be fixed in any desired relation. Each part has a plurality of holes at each end to be fixed to the fixing element the ends of the first members of the booms. During relative movement of the booms, telescopic movement between the parts 166 and 167 can take place if the pins are removed from the aligned holes 168 and 169.

It will be seen that the invention provides a number of modifications of the scaffolding structure described in our copending patent application No. 799,001 filed Feb. 13, 1969, and now abandoned.

I claim:

- 40 1. A transportable scaffolding structure of adjustable overall height, comprising:
at least two substantially rigid booms in superposed relationship, each in the general form of a right prismatic framework of polygonal planshape and substantially vertical edges and each comprising
45 I. at least three tubular upright members extending in non-coplanar arrangement along said edges at the apices of said polygonal planshape, each tubular upright member of one of said two booms being in substantially vertical coaxial alignment with a corresponding tubular upright member of the other of said two booms,
II. outwardly projecting flanges secured at the ends of said tubular upright members and having thereon a plurality of non-aligned attachment points, and
55 III. a plurality of intercrossed bracing members extending generally on the substantially vertical sides of said prismatic framework between adjacent tubular upright members and secured to the flanges thereof at said attachment points,
60 a number of boom spacer struts equal to the number of corresponding coaxially aligned tubular upright members of said two booms and extending generally vertically therebetween in interconnecting extension of the edges of the prismatic framework of said booms, each of said struts being in telescoping engagement with a corresponding tubular upright

member of at least one of said two booms for extension or retraction relative thereto, whereby said booms are guidedly slideable in bodily translational vertical displacement towards or away from each other to vary said overall height, and releasable locking means engageable with each telescopic tubular upright member and boom spacer strut assembly to fasten the same against telescoping movement, whereby said overall height is adjusted to a fixed value.

2. A scaffolding structure as claimed in claim 1, wherein said bracing members intercross both when viewed in horizontal directions perpendicular to the sides of said prismatic framework, and also when

viewed in a vertical direction perpendicular to said polygonal planshape.

3. A scaffolding structure as claimed in claim 1, wherein said outwardly projecting flanges secured at the ends of said tubular upright members have generally horizontal faces, and said bracing members have generally horizontal flat end portions securely applied against said flange faces.

4. A scaffolding structure as claimed in claim 1, wherein each of said boom spacer struts comprises two mutually telescopic upright sections, and releasable arresting means for locking said upright sections against telescopic relative displacement.
